UNITED STATES PATENT OFFICE

CLIFFORD E. WENTZEL, OF CINCINNATI, OHIO, ASSIGNOR TO THE BAHMANN IRON WORKS COMPANY, OF CINCINNATI, OHIO, A CORPORATION OF OHIO

MILL HOUSING

Application filed February 11, 1928. Serial No. 253,710.

This invention relates to improvements in cane mills, and particularly to the end housing or journal frames of the mill for journaling the juice expressing rolls, usually three in number, an upper and two spaced lower rolls, the lower each cooperating with the upper roll.

The cane is initially fed between the upper and one of the lower rolls, thence passes between the upper roll and a stationary guide or turn plate disposed between the two lower rolls and thence between the upper and second lower roll.

The guide or turn plate bridges the gap between the lower rolls and sustains the material in passing from one set of rolls to the second. The cane in passing over the turn plate, heavily compressed, produces considerable friction and requires a greater amount of power to move. Mill designers have generally sought to reduce the spacing between the lower rolls without reduction of diameter of the roll shafts, for the narrower the turn plate correspondingly less power is required to move the cane.

With the conventional mill housing construction, due to the tremendous pressure exerted between the rolls, for each end housing vertical bolts, tying the top journal cap, housing and bed plate, are employed to take up the vertical strains and these bolts govern the spacing of the lower rolls. The stresses to which the conventional vertical housing bolts are susceptible fix their diameters and these diameters, in connection with the diameters of the rolls and their respective shafts, fix the width of the turn plate.

Likewise, horizontal bolts extending through the housing for sustaining the opposite end caps for the lower roll shafts are employed and these with the vertical posts make a network of cross bolts within the housing which add considerable to the cost and weight of the housing and complicates assembly. For large mills considerable headroom is required for inserting and removing the vertical bolts together with a pit space in the foundation for heading or anchoring the vertical bolts to the base of the housing.

To express the juice from the sugar cane,

great pressure is required and the greater the pressure on the cane the higher the extraction of the juice. Consequently, the greater the strain produced in all parts constituting the mill. Obviously, the higher the extraction the greater the amount of sugar or sirup is obtained for a unit of cane.

With the present invention, the housings are made throughout of steel plates welded together and of a structure which permits roll shaft diameter greatly in excess of what is now used and eliminates the use of large tension or tie bolts of the conventional mill housing, adapting the three rolls of the mill to be brought closer together so that a minimum width of guide or turn plate can be employed. The steel housing is smooth on all surfaces, so that there are no crevices or depressions where cane juice can lodge and become sour.

Many advantages result from the steel housing, as comprehending a material reduction in weight of the mill, effecting considerable saving in freight charges and transportation, loading and handling costs, and reduces the liability to injuries through rough treatment in shipping, and is more susceptible to repair if injured. The mill does not require a bed plate in mounting, and the housing can be set directly upon a foundation, built up at the place of installation and preferably under a method included herein.

Other features relate to the detail structure of the housings and to the structure of the turn plate and foundation for the housings, all of which will be more fully set forth in the description of the accompanying drawings, in which:

Figure 1 is an end view of a cane mill showing, in detail, an end housing or journal frame thereof.

Figure 2 is a top plan view of the end housing or journal frame.

Figure 3 is a sectional view taken on line 3-3, Figure 1, detailing the mounting of the upper mill roll and also the mounting of one end of the turn plate.

Figure 4 is a sectional view taken on line 4-4, Figure 1, detailing the manner of securing the resistance blocks between the side

plates of the journal frames and also detailing the journalling of one of the lower mill rolls.

Figure 5 is a fragmentary side elevation 5 of a journal frame.

Figure 6 is a sectional view taken on line 6—6, Figure 5, detailing a lower mill roll journal and the resistance block containing the journal adjustment mechanism.

10 Figure 7 is a sectional view taken on line 7—7, Figure 3, detailing the mounting of the turn plate.

15 Figure 8 is a view looking toward the inner face of an end housing and showing the housing frame fabricated welded structure stripped of all the journals and resistance blocks.

20 Figure 9 is a side view of a pair of end housings set up on a foundation in their mill journalling relation, the housings stripped of all the working mechanism to bring out the fabrication thereof.

25 Figure 10 is a sectional view taken on line 10—10, Figure 1, detailing the manner in which the turn plate is secured in operative position within the mill.

30 The drawings disclose in detail only one complete housing for a mill for journalling one end of the roll shafts. A second housing for the opposite end of the shafts is of duplicate construction. The housings are independently mounted upon the foundation or bed plate and each is formed of a pair of steel plate side walls designated as side plates 35 1, 2, at definite spacing to accommodate for the capacity of journals necessary for a given weight and size of rollers and their shafts.

40 The side plates 1 and 2 are cut out to form openings 3—3—3, one for each of the roll shaft journals, adapting the journals and their shafts to be removed or inserted without disturbing the housings or unbolting the same from the foundation.

45 For the lower rolls, the bearing openings adapt the bearings and their roll shafts to be removed horizontally and for the upper roll vertically. Thus, for the lower rolls the housing side plates are cut out from their opposite end edges inwardly and for the top roll from their top edge centrally downwardly. The side plates at the cut-out portion for the lower roll journals are connected or joined together in their spaced relation by cross bearing plates 4—4 welded to the side plates.

50 55 The bearing plates preferably extend or overlie slightly beyond the outer surface of both side plates to provide protruding opposite edges so that the parts can be welded together by lines of fillet welding 6 along the opposite side edges of the bearing plates and lower base surface thereof, and preferably at the exterior sides of the side plates, facilitating the welding.

60 65 The cross bearing plates from seats or supports for adjustably sustaining the shaft

bearing boxes 7—7, while for the upper roll a pair of oppositely disposed cross plates 8—8 are employed for guidingly sustaining the upper journal 9, the cross plates providing guideways for an upper journal block. The 70 side plates at the journal for the upper roll are further provided with a semi-circular cross plate or segmental bushing 10 welded to the side plates in substantially the same manner as heretofore described for the plane 75 cross plates. The segmental bushing sustains the lower journal or brass section for the bearing of the upper roll.

The journal blocks or boxes are adjustable to accommodate for feed openings and roll 80 wear, with the mechanism for adjustment being the same as generally employed in the mills of this character, and as illustrated for the lower rolls comprises a horizontal screw 11 having its inner end abuttingly engaged 85 with the journal box 7. The screw 11 has threaded engagement with a stationary nut 12 mounted and socketed in a resistance block 13 suitably secured between the side plates. The resistance or spacer blocks 13 each are 90 held in place and fixed in position by taper pins 14 engaged through bushings 15—15 in the side plates. The bushings each extend through a bore in its respective side plate and are welded thereto circumferentially by 95 fillet welding.

A resistance block 13 is provided for each of the cut-out portions or journal openings of the housing, and comprises a casting having a central body portion which receives 100 the journal adjusting and abutment screws, gaps the journal opening, and is clamped to and between the side plates.

The resistance block at its opposite ends is provided with ear extensions 16—16 of the 105 width of the spacing of the side plates or bushings welded in the side plate and adapted to be securely clamped thereto by the taper pins 14 extending through the side plates and ears. The taper pins 14 are counter-turned 110 at one end and screw-threaded to receive a tightening nut 17 (see Figure 4) for drawing the pins within the bushings 15 welded in the side plates and within the ears of the resistance block, the nut having a bearing engagement with one of the bushings 15. The pins pass transversely through the side plates of the housings and, therefore, are in double shear and possess greater strength than a bolt of corresponding diameter placed 115 in tension. The strength of a bolt in tension is measured by its diameter at the base of the thread, while a bolt or pin in shear by its body diameter, and with the side plates at the point of bolt reception being reinforced by bushings through which the bolts pass, and is capable of withstanding the most severe pressure, to which a mill of a given size may be subjected, without injury to the bolt and housing.

120 125 130

The journal blocks or boxes 7 are of segmental form slidably mounted upon its bearing plate and each is adjusted outwardly by means of the screw rod 18, having its head 5 end engaged with the block and extending through a bore in the resistance block 13. A nut 19 is engaged upon its screw-threaded end, having a bearing against the resistance block. Upon rotating the nut after release 10 of the abutment screw, the bearing block can be drawn outwardly. The journal block abutment screw 11 is held against rotation by a lock collar 20 engaged upon the screw at the head end, pinned to the resistance block 15 and locked to the screw 11 by a set screw 21 engaged through the collar and bearing against the abutment screw.

The journal block and the mechanism for adjusting the same may follow various types 20 of construction and its detail of construction is optional insofar as it may concern the structure of the housing.

The side plates are further reinforced at their base by angle or brace plates 22 welded 25 to the side plates and base plate 23. The brace plates are preferably disposed at the outer sides of the side plates and of a number and spacing apart as may be required for a given size of housing. In the present instance, three 30 are illustrated for each of the side plates. The side plates centrally and vertically from the upper roll journal to the base are strengthened as a unit by a beam stiffener 24 disposed between the side plates and welded 35 thereto, and preferably of I-form.

For the upper roll journal, the segmental bushing 10 extends across the side plates at the base of the journal opening and is welded to the side plates and, as in the case of 40 the horizontal bearing plates for the lower roll journals, extends slightly beyond the outer sides of the side plates to facilitate in welding, and also for giving the same greater dimension.

45 The inner face of the bushing is of faceted configuration to receive a correspondingly configurated brass 26, adapting the same to be non-rotatably seated upon the bushing. The brass is provided with end flanges following a common practice for engaging over 50 the ends of the bushing to sustain the brass against longitudinal or axial movement. The segmental journal box or block 9 engaging the upper half of the upper roll shaft is slidably mounted upon the oppositely disposed vertical bearing plates 8—8 connecting with the side plates which are welded and secured to the side plates in substantially the same manner as the bearing plates for the lower 55 roll journals. The journal block or box may represent any type of construction and be held in place under pressure by means of screw, hydraulic or spring devices. The form shown, however, is merely conventional, not 60 forming a part of the present invention.

The side plates are further joined together at their base by the horizontal base plate 23. The base plate extends a suitable distance beyond the side plates to provide a definite marginal flange for bolting the housing to the 70 foundation structure.

Each housing, as a unit, is composed of a pair of side plates spaced apart and joined by a base plate, a central vertical stiffener beam between the side plates, and journal bearing supporting cross plates, all welded to the side plates together with the resistance blocks located between the side plates as journal abutments clamped between the side plates by taper pins. The housing, therefore, mainly comprises a structure fabricated from steel plates with the parts welded together into a very rigid unit capable of 75 standing excessive strains and pressures, and considerably lighter in weight than the conventional cast housing, and also offers a material reduction in cost of manufacture and 80 machining.

In fact, only a minimum amount of machining is required. Any of the parts may 85 be machined as required before they are assembled into a housing and welded together. This facilitates machine operations because of handling only comparatively small pieces, and thus, as large machine tools are not required to machine the housing as where the 90 housing is cast in one piece.

Rolled steel housing eliminates the large 95 horizontal and vertical bolts. On a large size mill with cast housings these bolts range from 100 4 to 6 inches diameter and of considerable length. When erecting, repairing and dismantling the mill, these bolts pass through cored holes in the housing and it is necessary 105 to have considerable space beyond the mill to accomplish this. The vertical housing bolts in a cast housing mill, pass through the housing, bed plate and down through a very heavy washer and to accomplish this the 110 foundation is cut out. This not only weakens the foundation, but offers less surface for the load of the mill. These depressions are objectionable because they offer lodging places for juice to become sour.

With the rolled steel housing the foundation 115 would be level on top.

Rolled steel is more uniform in structure than castings, consequently more uniform in strength. Due to unseen defects in rough 120 castings before machining there is usually considerable loss in labor when machining castings, because defects generally show up after the casting is being machined.

Large castings, such as used on a cane mill 125 require many cores and if these are not properly located, the casting cannot be used. With rolled steel any alteration or addition is readily made. The cost of making patterns, cost of pattern storage, including rent, insurance, interest and taxes, cost of carry- 130

ing obsolete patterns, is all eliminated, as well as patterns that are used only once. Also a smaller manufacturing space is required.

- 5 There are a large range of sizes required by cane mill manufacturers. For each size it is necessary to have, (with cast housings) a pattern with its numerous core boxes for each size. The diameter of the rollers determine the size and these diameters range from 8 inches to 34 inches with intermediate diameter every two inches. There are a number of styles, light, medium and heavy mills, each style also requires a different pattern, because the roll shaft diameters vary. It is often required to change the diameters of the roll shafts, according to a customer's specifications. This usually necessitates altering the housing pattern and occasionally requires a new pattern, which may only be used for this particular order. With the plate steel mill it is only necessary to arrange the steel parts comprising the housing to suit the conditions such as shafts and roll diameter and weld the parts together.

6 While reference has been principally made to housing for cane mills, it is apprehended that they may be included for other types of machinery.

- 7 The turn plate, which is disposed beneath the upper roll, is mounted to and between the housings. The inner side plate of each housing is provided with a bracket or wedge container of dove-tailed formation presenting a plate base 29 welded to the side plate and provided with a pair of oppositely disposed taper lugs 30—30 extending therefrom. Each lug provides an inclined support for a wedge 31 adjustably secured to the lug by means of a screw 32. A sectional trunnion journal block 33 is slidably carried by the wedge for supporting a trunnion 34 extending from one end of the turn plate 35. The base 29 of the bracket is centrally slotted to provide for additional welding surface intermediate of the base for welding the base to the side plate.

8 Trunnions are provided, one for each end of the turn plate, preferably clamped to the body or beam portion thereof to render the trunnion removable for convenience in renewing in the event of breakage or wear.

- 9 The drawings merely illustrate one end portion of the turn plate, the opposite end being of duplicate construction. It preferably comprises a beam body portion built up of a steel plate having bars welded to the longitudinal opposite ends with the plate disposed in a vertical plane in its position within the machine or mill. The upper bar edge 36 longitudinally is provided with a trunnion 37 for engagement into a longitudinal groove in the base surface of a head bar 38. The head bar provides the bridge or guide surface beneath the upper roll over which the

material passes as it is being transmitted by the rolls from one set to a second. The head bar is removably secured to the beam body by tie bolts 39 disposed at relatively opposite sides of the beam, engaged through the end bars of the beam and screw-threaded into the head bar. The turn plate or beam is clamped in position at its lower end by any suitable means for sustaining the same rigidly in position and capable of being angularly adjusted for swinging the same within the bearings of the trunnions, the clamping means as illustrated comprising a U-bolt 40 straddling a pintle 41 welded to and projecting from the base of the beam, the pintle resting in a shackle 42 bolted to the housing foundation with the U-bolt connecting with the shackle.

10 The housings are mounted directly upon the foundation and rest upon cross beams 43 of channel form imbedded in the foundation, the top flange of the beams projecting slightly beyond the top of the foundation and levelled up to receive the housing. The channel beams are tied together by bolts 44 each engaged through a spreader tube 45 having end engagement with the beams which are likewise imbedded in the foundation. The housings are secured in place upon the channel beams by bolts 46 anchored in the foundation and engaged through the base plate of the housing.

11 Having described my invention, I claim:

12 A housing or journal frame for cane mills and the like machinery, comprising, a pair of steel side plates in spaced parallel relation, the plates correspondingly having cut-outs, each cut-out extending from an edge of the plate inwardly providing an opening for the reception of a journal, cross plates welded to and bridging the side plates respectively at the cut-out bearing openings, each forming a platform for a journal, journal resistance and abutment blocks, one for each bearing opening disposed between the side plates and gapping the opening, and tapered clamp pins engaged through said blocks and through bushings welded to the side plates for clamping and binding the blocks and side plates, and a base plate welded to the lower horizontal edges of said side plates.

13 In witness whereof I hereunto subscribe my name.

CLIFFORD E. WENTZEL.
